UNITED STATES PATENT OFFICE.

ABRAHAM SPIRO, OF NEW YORK, N. Y.

HAND-BAG.

1,152,346.

Specification of Letters Patent. Patented Aug. 31, 1915.

Application filed April 21, 1915. Serial No. 22,812.

To all whom it may concern:

Be it known that I, ABRAHAM SPIRO, a citizen of the United States, and a resident of the city of New York, borough of Manhattan, in the county and State of New York, have invented a new and Improved Hand-Bag, of which the following is a full, clear, and exact description.

Among the principal objects which the present invention has in view are: to provide a hand bag with means for preventing the undetected opening thereof; to provide means for protecting the fittings of a bag of the character mentioned from filth or dirty accumulations; to provide a change receptacle disposed to afford easy access thereto; and to provide a bag of the character mentioned with a pocket receptacle independent of the main body of the bag or of the change receptacle mounted thereon.

Drawings.—Figure 1 is a perspective view of a bag constructed and arranged in accordance with the present invention, the bag being shown in the position where the compartments may be opened; Fig. 2 is a vertical cross section of the bag, showing the same in closed position.

Description.—As seen in the drawings, the article herein described has three compartments, to wit, the bag 7, the purse 8, and the pouch 9. The back 10 forms the outer side of the compartment 9, and is structurally connected with the closure flap 11 by means of an insert 17. The flap 11 is fastened to the front of the bag 7 by means of fastening devices of any suitable character, such as the glove fasteners 12 and 13 shown in the drawings. The inner side of the bag 7 and of the pouch 9 is formed by a member 14. The member 14 is connected by inserts 16 with the front of the bag 7. The inserts 16, member 14, and front of the bag 7, are conventionally secured to the hand-bag frame 18. The frame 18 is furnished with suitable fasteners, such as the spring knobs 19. Any other suitable and conventional fasteners may be employed. The insert 17 is so arranged between the back 10 and the closure flap 11 as to form a pocket for covering the upper part of the frame 18 and the knobs 19. The pocket thus formed prevents access to the knobs 19 when in service the fasteners 12 and 13 are secured. The bottom of the insert 17 is also utilized as the bottom of the purse 8, the sides of said purse being secured by stitch-

ing 20 to the back 10 and closure flap 11, as shown best in Fig. 2 of the drawings.

The purse 8 is provided with fastening knobs 21 similar in design to the knobs 19 mounted on the frame 22.

In service and when the flap 11 is secured by means of the fasteners 12 and 13, the purse is inverted and the opening thereof is extended into the pouch 9, as seen best in Fig. 2 of the drawings. When the bag is thrown open to the position as shown in Fig. 1 of the drawings, the bag 7, the purse 8, and the pouch 9 are all upturned to afford easy access thereto. This arrangement permits the person carrying the bag to deposit a handkerchief in the pouch 9, which may be extracted therefrom without opening either the bag 7 or the purse 8. Also, money or change which is carried in the purse 8 may be extracted therefrom without requiring the opening of the bag 7. Also, it will be observed that access to the bag 7 is freely acquired without necessitating the opening of the purse 8. Further, when the bag is closed, it will be observed that if perchance the purse 8 is left open, the contents thereof, if dropped from said purse, will fall into the pouch 9 and thereby be prevented from being lost.

It will be seen that the arrangement of the purse 8, pouch 9 and flap 11 is such as to baffle a thief endeavoring to pilfer from the bag, or at least render the operation so difficult as to notify the owner. Further, the top of the bag formed by the insert 17 is normally so close to the handle 23 provided for carrying the bag that the sleeve of the person carrying the bag prevents the lift of the pocket to gain access to the fasteners 19 or 21.

Claims:

1. An article as characterized, comprising a plurality of receptacles, each having an opening edge; a connecting back structurally uniting said receptacles to hold the same relatively inverted in service, said back forming a carrying pouch intermediate said receptacles; and a closure flap extending in front of said receptacles when closed.

2. An article of manufacture, comprising a plurality of receptacles, each having an opening edge; a connecting back structurally uniting said receptacles to hold the same relatively inverted in service, said back forming a carrying pouch intermediate said receptacles; a closure flap extending in front

of said receptacles when closed; and a fastener for holding said flap in closed position.

3. An article as characterized, comprising a plurality of receptacles, each having an opening edge; a connecting back structurally uniting said receptacles to hold the same relatively inverted in service, said back forming a carrying pouch intermediate said receptacles; and a closure flap extending in front of said receptacles when closed, said flap being partially connected with said back to form an enveloping pocket for the openings of said receptacles.

4. An article as characterized, comprising a plurality of receptacles, each having an

opening edge; a plurality of locks, one for each of said receptacles; a connecting back structurally uniting said receptacles to hold the same relatively inverted in service, said back forming a carrying pouch intermediate 20 said receptacles; and a closure flap having a pocket for enveloping said locks of said receptacles when in closed relation.

In testimony whereof I have signed my name to this specification in the presence of 25 two subscribing witnesses.

ABRAHAM SPIRO.
